LUGGAGE AND METHOD OF MAKING SAME

Leo Horwitz, Chicago, Ill.

Application December 8, 1948, Serial No. 64,205

3 Claims. (Cl. 190—28)

1

The present invention relates to articles of luggage and to a method of constructing various articles of hand luggage in which fabric or leather is employed as a principal covering material and in which a metallic frame outlines the covering and gives form and rigidity as well as locking securement.

Articles of hand luggage which may have various shapes ranging from the elementary rectangular to hat box curvatures include also a range of variations in proportion. The present invention, although illustrated in a simple embodiment of rectangular outline, lends itself particularly well to adaptation within the full gamut of designs to which these articles are customarily subjected. In the conventional process of manufacture a steel framework is provided in which strip members usually of flat rod or angular components are riveted or welded together to form the outlining framework, and upon this framework there is placed a covering material chosen for its lightness of weight and/or for its attractiveness of appearance. Luggage cases usually consist of two elements which may be of identical depth or one may be deeper and the other shallower, the two elements being hinged together at their metal framework so as to swing shut and form a portable container that may be carried by a handle and may be suitable for storage of personal articles, samples or wares.

Depending upon the precise nature of objects to be carried, cases are variously constructed with regard to load content. However, for personal use and where the load content is relatively light, tensile strength and structural characteristics are regarded as secondary to appearance and portability. The fabric casings are usually secured to their metal framework and particularly to their mouth lining edging strips by closely placed riveted securements. These securements which, under known methods of construction were deemed necessary to effect the proper integration between metal and fabric or metal and leather, are deemed to diminish, to a degree at least, from aesthetic qualities of the luggage and this has been particularly recognized in respect to modern streamlining trends where simplicity and straight lines are favored over pattern interruptions and filigree.

With a view towards eliminating the practice of riveting in effecting securement between certain parts of the metal framework and the fabric components of luggage cases, it is proposed to provide herewith a new method of construction in which this association is effected by a forming

2

process which will clinch the edging metal in an even and continuous manner to the adjacent fabric or leather.

More significantly in accomplishing these ends there has been achieved a construction which will utilize the tarnish resistant and durable qualities of stainless steel as a metal lining substance and in so doing take advantage of certain metallurgical characteristics. In this way there is given to the end product beauty of appearance and structural strength beyond the limits at which luggage articles have been made heretofore.

Briefly stated a principal object of this invention is to obtain a luggage construction in which the metal framework is more securely joined with the fabric or leather casing material throughout the full perimeters of juncture without the use of localized securing elements.

Another object of this invention is to devise for luggage cases an edging strip of such cross section that the strip can be made of stainless steel and to utilize certain metallurgical characteristics thereof in effecting a positive clinching securement which is continuous along all perimetric lines of junction and which may be applied to opposing components by simple reversal to effect secure and aesthetic construction qualities.

Another object of the present invention is to devise a method for applying in symmetrically opposite relation an edging strip on two opposed luggage casings by processes of rolling, shaping and compressing under conditions adaptable to production methods of manufacture.

Still other objectives of this invention are such as will appear during the course of the following detailed description and explanation and such as will be manifest by an understanding of the hereunto appended claims.

In the accompanying drawings and in the following specification like reference characters designate corresponding parts throughout.

Fig. 1 is a perspective view of an article of hand luggage featuring the aesthetic qualities which may result from the practice of this invention;

Fig. 2 is a fragmentary perspective view of the edging abutments and clincher construction having embodied therein the essential principles of the present invention;

Fig. 3 is a fragmentary perspective view of an edging strip during formation treatment from which evolves a rounded corner structure;

Fig. 4 is a fragmentary perspective view of a

similar treatment of the same edging strip for obtaining a reverse corner formation;

Figs. 5 through 7 are fragmentary sectional views of various manufacturing steps which may be employed in the attainment of clincher binding between the edging strip and the fabric or leather which comprises the casing elements;

Fig. 8 is a fragmentary perspective view of the bottom of a luggage article illustrating a manner of applying a reinforcing gusset and hinge assembly;

Fig. 9 is a perspective view of a special forming tool which may be employed in the shaping and closing operations which concern themselves with the various types of luggage edging according to the present invention;

Fig. 10 is another perspective view of the apparatus illustrated in Fig. 9 featuring its use as a clamping or pinching mechanism;

Fig. 11 is another perspective view of the same apparatus featured in Figs. 9 and 10, showing the clamping jaws in their open condition;

Fig. 12 is a transverse sectional view through a pivot stud which forms the turning center of the application tool featured in Figs. 9 through 11;

Fig. 12a is a fragmentary sectional view of a modified form of turning center tool adapted for use in rotating and forming the liner strip about its flat surface.

Fig. 13 is a fragmentary sectional view taken approximately on line 13—13 of Fig. 16, illustrating the position occupied by the liner strip during formation operations;

Fig. 14 is a detailed sectional view of the clamping jaw relationship of the application tool during forming operations;

Fig. 15 is a fragmentary enlarged detailed view of the clamping jaw relationship of the forming tool during clincher or pinching operations;

Fig. 16 is a plan view of the special tool illustrated in Figs. 9 through 11;

Fig. 17 is a fragmentary detailed view through a portion of the mechanism shown in Fig. 16 and is taken as indicated by the viewing line 17—17 on Fig. 16; and

Fig. 18 is an enlarged sectional view through a portion of the edging strip where the flexible spacer pack terminates within an indefinite length of strip stock.

In the accompanying illustrations the reference numeral 21 designates generally a handbag or suitcase such as is appropriately constructed of leather casing elements 22 and 23 made up of tailored component sections blocked into the requisite shapes and stitched as at 24 in the well known manner in which these elements have been assembled under various seam patterns and arrangements. The case elements 22 and 23 are each lined at their mouth opening as at 25 and 26 on three sides, namely, the top and end sides of the luggage unit, while the bottom, Fig. 3, is correspondingly lined by hinge assembly 29 which may be of a continuous sleeve and pintle arrangement, such as is particularly termed a piano hinge association. The hinge is ultimately secured to the edging strips 25 and 26 by means of reinforcing gussets 27 which may be welded or riveted to the hinge and to the strips in order to afford a reinforcement thereat.

Alternatively the gussets 27 may be provided with a hinge juncture as at 28, in which case the same lining strip may continue all the way around on the four sides of the luggage unit 21. The tailored components of the case elements are

turned under as at 31 and 32 and stitched to bottom panels 33 while at 34 there are secured glider buttons to support the case in its upright position against undue wear and abrasion.

In the type of handbag illustrated the two case elements 22 and 23 are of substantially identical breadth or depth, meeting one another in edge to edge juncture. It is also contemplated that the constructional arrangements which will later be discussed in greater detail are adaptable to case constructions and designs where this juncture is offset so that one case element is deeper than the other one, or even where one case element is so shallow so as to constitute merely a cover to the other one which comprises nearly all of the suitcase width. A carrying handle 35, of Fig. 1, may be pivotally supported as at 36 in a pair of trunnion pins riveted to one or the other of the liner strips 25 or 26. Also a pair of matched suitcase locks 37 may be secured to one of these strips with the other of the strips provided with lock bolt receiving apertured brackets as is well known in the art to which this invention pertains.

In order to maintain the shape of rectangular as well as of circularly outlined suitcases, a framework of steel or heavy fibre is usually provided which reinforces the outermost peripheral limits meeting the edging strips 25 and 26 at the corners as by riveting or welding, but since these details of construction are not significantly concerned in the present invention, it will suffice to say that any suitable mode of bracing may be contemplated for use in conjunction with the strips 25 and 26 which will serve the general objectives. It is to be noted that whereas the edging strips of suitcases heretofore would have been secured to the cases 22 and 23 by spaced securement elements such as rivets, the present edging strips are such that they may be secured to the casings 22 and 23 by clamping or clinching securement, detailedly illustrated in Fig. 2, where the edge of case 22 is held by the clincher lips 41 and 42 of strip 25, and where the case element 23 is correspondingly held by the clincher lips 43 and 44 of strip 26.

It will be observed that strips 25 and 26 may be made of the same stock material applied in reverse manner so that the doubled flange 45 of strip 25 overlaps the doubled flange 46 of strip 26, each abutting the shoulder portion 47. The two case components are lined at their abutment edges with these metal edging strips to effect a positive metal-to-metal contact as between the two case components during closure. By the expedient of symmetrical flange overlap of the same stock strip an economy of material is achieved. This overlap and abutment cooperation between the two strips permits both of them to lie in the same plane, a feature which is recognized as materially advantageous over heretofore known structures in which overlap of one strip by the other involved a perimetric protrusion. Accordingly, attention is directed to a major utilitarian achievement which affords a strong and rugged interengagement between the two case elements under conditions of significantly more attractive design.

While the strip elements 25 and 26, being made of the same stock of sheet material folded or rolled into the form best illustrated in Figs. 3, 4 and 14, may be manufactured of any metallic substance, a preferred choice for this purpose for several reasons has been found to be a formable or ductile stainless steel. This type of steel pos-

seses ductile and tensile strength characteristics which are critically suitable to the mode of application which will now be described in particular and which affords a wear resistant tarnish free substance that may be applied and secured to the cases by a clamping or pinching operation.

In its rolled condition the stock strip should have a section as best indicated by the dotted outline of Fig. 14 during which the doubled over flange 45 stands open with a V space 48 between its elements while the sides 49 and 51 flare outwardly at continuations of the same angle as is indicated by the V space 48. The distance between the clincher lips 41 and 42 is wide enough to receive the leather fringe of the case elements 22 and 23 even in places where these elements are of double thickness, such as at seams 24. There will now be explained the structural details of a mechanism and its manner of operation for accomplishing the corner bending of the stock strip whereby an aesthetically attractive one piece continuous construction is achieved as a result of which the improved design here disclosed is accomplished economically.

Particular attention is now directed to Figs. 9 through 13 which feature a special multiple purpose tool that achieves all of the bending and crimping operations necessary for the application of stainless steel strip of the class herein contemplated to suitcase elements. The reference numeral 61 designates generally a bed plate which may be the top of a bench upon whose surface there is secured as by bolting at 62 a base plate 63. Through an aperture in plate 63 (see Fig. 12) there extends in a vertical direction a cylindrical pivot stud 64 that either may be welded to the base plate, or may be secured to a collar 65 by one or more radially extending set screws, the collar being anchored to the base by vertically extending bolts 67.

The stud 64 constitutes a vertical pivot about which a portion of the fixture swings, and carries a forming mandrel 68 shaped as at 69 whereby to receive the strip in one of two alternative positions. Another mandrel which is interchangeable with mandrel 68 is shaped as indicated at 71 (see Fig. 12^a) for receiving the strip in its other position. In this way both inside and outside curvatures may be shaped on the same apparatus, although if desired two separate complete bending fixtures may be employed, one for bending the curvatures with the flange innermost as indicated in Fig. 3 and the other for bending the curvatures with the flange 45 or 46 outermost as indicated in Fig. 4.

A hold down plate 72, shaped as best indicated in Fig. 16, is bolted as at 73 to the mandrel 68, whereby the entire assembly is rotatably anchored, and this plate 72 is preferably notched as at 74 and flattened as at 75 so as to fit a complementary top block portion 76 associated with a swinging jaw 83 of section 77 of the unit. The square notch and shoulder engagements which have been designated 74 and 75 extend down through the forming mandrel 68 and the work-engaging face of jaw 83 merges into a similarly shaped work-engaging face of mandrel 68, so that the mandrel together with the fixture 77, can swing as a unit about pivot stud 64 in order to roll a strip about the exact curvature of arc which is indicated by the several diameters of the mandrel. This rotation is confined to an accurate 90 degrees of movement by the provision of a stop pin 78 located in the bed plate 63 at a

point where it is encountered by the edge 79 of a pivotable plate 81, see also Figs. 9 and 12. A similar limit pin 82 is encountered by the edge 83 of plate 81 whereby is established the other extremity of position at which fixture assembly 77 is disposed.

In addition to the swinging fixture 77, there is provided a stationary fixture generally designated 87, see Figs. 9, 10 and 11. Each one of the 10 clamping units 77 and 87 comprises a relatively stationary jaw block 88 or 89, the block 88 being pivotable about the stud 64, and a cooperating jaw portion 91 or 92 which is slidable towards and away from its companion jaw block upon 15 actuation of its toggle lever 93 or 94, respectively.

As will be observed from Figs. 9 and 10, lever 93 is pivotally articulated as at 95 in the trunnion blocks 96 of jaw member 91, and in identical manner lever 94 is pivotally articulated as at 97 20 in the trunnion blocks 98 of the jaw member 92, both sets of trunnion blocks 96 and 98 being bolted as at 99 to their respective jaws.

In addition to the just described pivotal articulation each one of the toggle levers 93 and 94 is 25 additionally pivoted as at 101 and 102 to a pair of toggle links 103 and 104, the latter being in turn pivoted as at 105 and 106 in upstanding trunnion plates 107 and 108.

From the foregoing, it will be readily understood that as the toggle levers 93 and 94 are 30 swung from their horizontal positions, as indicated in Figs. 10, 13 and 16, to their vertical positions as indicated in Figs. 9 and 11, their related clamping jaws 91 and 92 are withdrawn from 35 their clamping or effective positions to their ajar or release positions.

In order to accommodate for various conditions such as may result from wear or fluctuations in stock specifications, adjustment means 40 are provided whereby the upstanding trunnions 107 and 108 may be laterally displaced and thereat securely held towards the end purpose of locating or adjusting the shiftable jaws 91 and 92 in respect to the pivotal jaws 81 and 89. This 45 adjustment is achieved with critical accuracy by securing end plates 109 and 111 to the bed plates 81 and 112 of the respective units 77 and 87 and by mounting adjustable abutment bolts 113 and 114 in said end plates, each of said abutment 50 bolts being provided with a check nut so that when threaded into the body of its respective plate 109 or 111, it may be secured against inadvertent change. After each pair of trunnion members 107 and 108 is accurately located 55 through the aforescribed adjustable limit screws 113 and 114, the assembly including each pair of said members 107 and 108 is clamped securely at its located position by recessed screws 116 which thread into spacer blocks 117 located 60 between each pair of said elements.

In order to make a given set of clamping jaws 91 and 89, or 92 and 89, serviceable for various clamping or crimping operations, there has been devised an interfitting relationship as shown in 65 Figs. 9 through 13, a modification being portrayed in Figs. 14 and 15, whereby one of the jaws, preferably the relatively fixed one, is fitted with a straight rectangular recess generally designated 121, while its companion jaw 92 is provided with a stepped projection generally designated 122. When these two jaw members are brought together, as indicated in Fig. 15, the space between their meeting portions designated 123 and 124 is such as to grasp and crimp the 70 overhang flange portion 45 or 46 about its bend

7

line 125 until the sides 127 and 128 of a metallic binding strip are firmly compressed about the leather, fabric, or other case material 129.

Under an alternative condition of operation, when the movable jaw 92 is brought into engagement with the stationary jaw 89 after the strip of material has been placed into the recess 121, a condition such as that illustrated in Fig. 13 is achieved, at which the sides 127 and 128 of the binder strip are held apart by a flexible laminated strip 131, see also Fig. 18. The purpose of this gripping engagement will best be understood by giving attention to the disclosure in Figs. 16, 17 and 18. In these illustrations, it will be observed that when the clamping jaws 91 and 89 grip between them a length of the binding strip 25 or 26 for the purpose of accomplishing the curvature bending illustrated in Figs. 3 to 7, clamping jaw 92 is preferably relaxed so as to permit the strip to slide in the jaw aperture as the fixture 17 is rotated about the stud 64. During this movement, depending upon whether the bend shown in Fig. 3 or that shown in Fig. 4 is to be accomplished, a corresponding mandrel on the stud 64 is provided which will conform with the profile of the strip in accordance with its interior surface.

As viewed in Fig. 16, the flexible laminated strip 131 will be pulled toward the right, until it is taut, after which it will slip in the strip 25 until the full 90 degree turn is completed. In order to assist in the free movement of the flexible laminations 131 in the strip 25, the outermost ones of them are preferably inturned, as best indicated in Fig. 18 at 135 and 136. Since the same fixture is being employed for several purposes, as has already been indicated, the strips 131 are preferably anchored as at 137, Fig. 16, in a pivoted clamping fixture in which a pivot stud 138 is provided that passes through the fixture 137 and the upstanding flange 139 of an angle member that is secured to the bench 61. By providing the described pivotal arrangement and a limit block 142 to be encountered by the fixture 137, the strips 131 may normally be disposed in horizontal position for service during the bending operation and may be swung out of the way as indicated in the dotted outline, Fig. 17, when the principal fixture is to be employed for crimping to secure the inwardly turned clincher edges 43 and 44 to the material 22 or 23.

After a 90 degree bend has been formed, the strip is freed so that its spaced sides 127 and 128 will again spring open to receive the case material 22 or 23. The edge of each case, after it has been fully inserted in its respective edging strip, is then clamped in the vise jaws in the manner illustrated in Fig. 15, the elements of the flange 45 (or 46) being compressed so that the bend line 125 lies along the flat side of the strip, the sequence of clamping operations being indicated in Figs. 5, 6 and 7. As a consequence of clamping one side, Fig. 6, between the jaws 89 and 92, the strip is effectively closed to a point well beyond the start of the corner bend. When, thereafter, the jaws 91 and 88 are closed as indicated in Fig. 7, the remainder of the bend is also closed as a result of a phenomenon of bending by reason of which the inside flange 127 or 128 (depending upon whether the Fig. 3 or 4 type of bend is made), having nearly as much metal throughout its length as the outside curvature, coupled with the fact that the outside curvature in attempting to describe a greater radius is drawn slightly inward, there

8

results a combined effect of mutual closure so that the case material 22 or 23 which is disposed in the area of curvature is effectively gripped and held as though that portion had also been squeezed together, as by the operation illustrated in Fig. 15. Under actual separation tests, it has been found that this gripping within the area of the curvature is so effective as not to require a corner pinching operation in order to obtain the necessary adherence between the strip and its case material.

While the present invention has been explained and described with reference to specific contemplations of apparatus and methods of procedure, it will be understood nevertheless that numerous variations and modifications may be incorporated without departing from its essential spirit or scope. Accordingly, it is not intended to be limited by the details of illustrations in the accompanying drawings nor by the particular language used in the foregoing description except as indicated in the hereunto appended claims.

The invention claimed is:

1. A method of edge trimming the receptacle components of suitcases or similar articles which comprises the steps of forming a ductile stainless steel strip into a channel member comprised of a flat side element and an opposite offset side element so as to present a foremost lapping edge of doubled strip steel and a rearmost portion of spaced gripping flanges having inwardly turned biting ridges, forming corner turns opposingly in lengths of said channel member to correspond with the peripheral dimensions of suitcase receptacle components, inserting the edges of said receptacle components into the spaces of said formed channel members, and compressing the foremost lapped edges of said channel members to effect a closing together of said inwardly turned biting edges to engage securely against the inserted component edges.

2. An article of luggage comprised of opposed case elements having mutually abutting lip portions, a binding strip made of sheet metal and formed so as to have a cross-section consisting of an off-set foremost lapping flange, spaced sides, and inwardly turned clincher edging, the binder strip of one of said case elements being formed to correspond with the lip profile of said case elements and having its said lapping flange innermost, the binder strip of the other of said case elements being also formed to correspond with the lip profile of said case elements but having its lapping flange outermost, the metal of which said binding strip is made being of such hardness and ductility characteristics as to receive and retain a compression set after its profile formation is completed by pinching together of its lapping flange to cause its clincher edging to bite into the case element lip portions inserted between its spaced sides.

3. An article of manufacture comprising an edging binder strip for luggage case elements consisting of a web of marginally ductile spring metal doubled-over upon itself so as to provide coextensive sides, one of said sides being substantially flat and having its free edge bent inwardly to face the other side and to afford thereby a narrow clincher flange, the other of said sides being longitudinally off-set whereby to afford a foremost section angling significantly away from surface abutment with its related portion of said first-mentioned side and a spaced section whose free edge is bent inwardly to form a clincher flange and to face said first mentioned clincher

flange, the ductile quality of said spring metal being such as to permit a set to be imparted to the doubled-over fold of said web by a compression force applied thereto for bringing into mutual surface abutment said foremost sections of said sides.
